SPERMICIDAL VAGINAL SUPPOSITORIES

William C. Ward, Norwich, N. Y., assignor to The Norwich Pharmacal Company, Norwich, N. Y., a corporation of New York

No Drawing. Application June 6, 1950,
Serial No. 166,528

6 Claims. (Cl. 167—64)

This invention relates to spermicidal vaginal suppositories.

The vaginal suppository which I have invented is particularly useful in the practice of feminine hygiene to secure inner cleanliness and in the elimination of objectionable odors. In the past, the practice of feminine hygiene has included the use of a vaginal douche consisting of an aqueous solution of a powerful antiseptic or the use of a vaginal suppository containing a small percentage of a powerful antiseptic followed by an aqueous vaginal douche. Deodorization of the vaginal tract as practiced in the past has consisted in the use of substances which possess odors designed to mask or cover up the less desirable odor whose effect is sought to be overcome. Neither of these practices has been completely satisfactory: Many of the antiseptics which have been employed have a tendency to irritate the vaginal mucosa if used too frequently or it not sufficiently diluted; and the odors of the substances which have been used to mask or cover up the less desirable odors in the vaginal tract are in themselves subject to objection.

I have discovered that a small percentage (about 0.2%) of a quaternary ammonium compound can be incorporated in a waxy vehicle or base comprising a non-ionic, surface-active, hydrophilic material which is solid at normal room temperatures but which melts rapidly at inner body temperature (37° C.) to provide a non-irritating suppository which is both antiseptic and deodorant and which also possesses valuable spermicidal activity. The quaternary ammonium compounds which I use as active antiseptic, deodorant and spermicidal agent in the practice of my invention are represented by the formula:

in which X=H or CH₃.

The two compounds which are represented by the above formula are, respectively: di-isobutyl cresoxy ethoxy ethyl dimethyl benzyl ammonium chloride, monohydrate; and di-isobutyl phenoxy ethoxy ethyl dimethyl benzyl ammonium chloride, monohydrate. Each of those compounds is at present marketed by Rohm & Haas Company, Washington Square, Philadelphia 5, Pennsylvania. The former is marketed under the trade name "Hyamine 10-X" and the latter is marketed under the trade name "Hyamine 1622." For purposes of brevity, those compounds will be referred to herein by those trade names.

The waxy base or vehicle which I prefer to use in the practice of my invention does not irritate the vaginal mucosa. It melts within a few minutes after it has been placed in the vagina to provide a liquid which, by virtue of its hydrophilic and surface-active character, emulsifies itself in the aqueous body fluids and rapidly coats the vaginal walls with a film which is rendered antiseptic, spermicidal and deodorizing by the quaternary ammonium compound, and which affords to the quaternary ammonium compound an optimum opportunity to function. The concentration of the quater-

2

nary ammonium compound at which this result is achieved is well below the toxic level of that material and at such concentration it is well tolerated by the vaginal mucosa and causes no irritation or other untoward reactions therein.

The vaginal suppositories embodying my invention are substantially odorless and it is evident that the deodorizing action thereof is due to the elimination rather than the masking of objectionable odors in the vaginal tract.

In order that my invention will be fully available to those skilled in the art, some formulations for the preparation of suppositories embodying my invention will be described briefly:

Example 1

	Parts by weight
A. Sorbitan monostearate polyoxyethylene derivative containing 4 oxyethylene units per mol	60.0
B. Sorbitan monolaurate polyoxyethylene derivative containing 20 oxyethylene units per mol	39.8
C. Hyamine 10-X	0.2

A suppository is prepared from this formulation by heating and mixing ingredients A and B, which comprise the base, and ingredient C is dissolved in the molten mixture of ingredients A and B. The melted mass is then molded in the form of a suppository and allowed to cool and harden.

Example 2

	Parts by weight
A. Polyoxyethylene palmitate containing 20 oxyethylene units per mol	99.8
B. Hyamine 10-X	0.2

Ingredient A, which comprises the base, is melted and ingredient B is dissolved therein. The melted mass is then molded in the form of a suppository and allowed to cool and harden.

Example 3

	Parts by weight
A. Cocoa butter	50.0
B. Polyoxyethylene glucose distearate containing 6 oxyethylene units per mol	42.0
C. Polyoxyethylene sorbitol pentastearate containing 6 oxyethylene units per mol	7.8
D. Hyamine 10-X	0.2

Ingredients A, B and C, which comprise the base, are heated and mixed, and ingredient D is dissolved in the molten mixture. The melted mass is then molded in the form of a suppository and allowed to cool and harden.

In each of the above formulations, Hyamine 1622 may be substituted for Hyamine 10-X. Furthermore, the ingredients which are employed to provide the waxy base for the suppositories described in those specific embodiments of my invention may be replaced by other ingredients of like character. Changes in the suppository base may entail slight changes in the percentage of the Hyamine 10-X or Hyamine 1622 which is used. However, I prefer to maintain the proportion thereof at about 0.2% as I have found that vaginal suppositories containing such quaternary ammonium compounds at that concentration may be used as often as desired without causing irritation.

What I claim is:

1. A spermicidal, vaginal suppository comprising a base of non-ionic, hydrophilic, surface-active polyoxyethylene wax containing from about 4 to about 20 oxyethylene groups per mol which is solid at normal room temperatures and which melts rapidly at 37° C., and about 0.2% of a quaternary ammonium compound represented by the formula:

in which X is a member of the group consisting of H and CH₃.

2. A spermicidal, vaginal suppository comprising a base of non-ionic, hydrophilic, surface-active polyoxyethylene wax containing from about 4 to about 20 oxyethylene groups per mol which is solid at normal room tempera-

tures and which melts rapidly at 37° C., and about 0.2% of di-isobutyl cresoxy ethoxy ethyl dimethyl benzyl ammonium chloride, monohydrate.

3. A spermicidal, vaginal suppository comprising a base of non-ionic hydrophilic, surface-active polyoxyethylene wax containing from about 4 to about 20 oxyethylene groups per mol which is solid at normal room temperatures and which melts rapidly at 37° C., and about 0.2% of di-isobutyl phenoxy ethoxy ethyl dimethyl benzyl ammonium chloride, monohydrate.

4. A spermicidal, vaginal suppository comprising 60.0 parts of sorbitan monostearate polyoxyethylene derivative containing 4 oxyethylene units per mol, 39.8 parts of sorbitan monolaurate polyoxyethylene derivative containing

20 oxyethylene units per mol, and 0.2 parts of a quaternary ammonium compound represented by the formula:

in which X is a member of the group consisting of H and CH₃.

5. A spermicidal, vaginal suppository comprising 99.8 parts of polyoxyethylene palmitate containing 20 oxyethylene units per mol, and 0.2 parts of a quaternary ammonium compound represented by the formula:

15 in which X is a member of the group consisting of H and CH₃.

6. A spermicidal, vaginal suppository comprising 50.0 parts of cocoa butter, 42.0 parts of polyoxyethylene glucose distearate containing 6 oxyethylene units per mol, 7.8 parts of polyoxyethylene sorbitol pentastearate containing 6 oxyethylene units per mol, and 0.2 parts of a quaternary ammonium compound represented by the formula:

in which X is a member of the group consisting of H and CH₃.
